DESIGN FOR A DRAWER PULL OR SIMILAR ARTICLE

Herman E. De Vries, New York, N. Y., assignor to
H. T. Cushman Mfg. Co., North Bennington,
Vt.

Application May 6, 1941, Serial No. 100,805

Term of patent 7 years

To all whom it may concern:

Be it known that I, Herman E. De Vries, a citizen of the United States, residing at New York city, in the county and State of New York, have invented a new, original, and ornamental Design for a Drawer Pull or Similar Article, of which the following is a specification, reference being had to the accompanying drawing, forming part thereof.

Figure 1 is a front elevation of a drawer pull showing my new design;

Figure 2 is a top plan view of the drawer pull;
Figure 3 is a bottom plan view of the drawer pull;

Figure 4 is an end elevation of the drawer pull; and

Figure 5 is a section taken on line 5—5 of Figure 3.

I claim:

The ornamental design for a drawer pull or similar article, substantially as shown.

HERMAN E. DE VRIES.
